(57) CLAIM

The ornamental design for a visor as shown and described.

DESCRIPTION

FIG. 1 is a front right perspective view of a visor showing our design;

FIG. 2 is front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

Colors form no part of the claimed design. FIGS. 1-7 include broken lines that are included for the purpose of illustrating portions of the visor that form no part of the claimed design.

1 Claim, 7 Drawing Sheets
